UNITED STATES PATENT OFFICE.

NOEL PEMBERTON-BILLING, OF HERTFORD, ENGLAND.

DOMESTIC HEATING AND COOKING APPARATUS.

1,349,096.

Specification of Letters Patent. Patented Aug. 10, 1920.

Application filed July 23, 1919. Serial No. 312,853.

To all whom it may concern:

Be it known that I, NOEL PEMBERTON-BILLING, M. P., a subject of the King of England, residing at Hertford, in the county of 5 Hertford, England, have invented certain new and useful Improvements in Domestic Heating and Cooking Apparatus, of which the following is a specification.

This invention relates to domestic heating- 10 and cooking-apparatus, its object being the provision of means conveniently for application to an ordinary domestic heating-stove whereby said stove can be employed also for cooking.

15 According to the present invention, for a domestic stove having a chimney-damper there is provided a fixed or removable front chamber situated in front of a fire-place opening in the stove and having within it 20 adjustable or other baffles, a flue connecting the interior of the rear portion of the chamber with the fire space of the stove to lead the draft from the latter into the chamber to be guided therein by baffles, and flues leading 25 from the top of the chamber at the right and left of it into communication with the chimney above the chimney-damper.

Preferably the said fire-place opening has 30 grate bars disposed in a vertical plane and the aforesaid front chamber is situated in front of the said grate bars and has a central draft opening in its rear face opposite the grate bars to lead the draft from between them into the chamber.

35 These and other features of the invention will be more clearly understood from the following description taken in connection with the accompanying drawings which illustrate one preferred form of the invention, and in 40 which—

Figure 1 shows an elevation of those portions of the stove relevant to the present invention;

Fig. 2 is a section on the line 2—2 of Fig. 45 1 and

Fig. 3 is a section on the line 3—3 of Fig. 1.

Like letters indicate like parts throughout the drawings.

50 In the construction illustrated the stove is shown diagrammatically as having a fire-chamber A with a normally open fire-place opening A¹ and grate bars A² disposed in a vertical plane. A horizontal grate A³ is also 55 shown for supporting the fire.

Situated in the front of the grate-bars A²

is a front chamber B closed by top and bottom plates B¹, B² and a curved front plate B³. The sides of the chamber are closed by vertical webs B⁴ radiating outwardly from the fire-chamber A.

In the example illustrated, the fire-chamber A is shown as surrounded by an outer jacket C, of which portions C¹ extend into the space between the webs B⁴ and constitute 65 portions of a rear face of the front chamber B. The space C² between the portion C¹ constitutes a port or flue which communicates between the fire-place opening and the front chamber B.

70 Within the front chamber B are baffles D hinged about vertical hinges at D¹. Thus in the position shown in full lines in Fig. 2 their inner ends come close up against the extremities of the portions C¹ and provide a 75 central passage within the chamber B through which the draft from the fire must pass before it can reach ports E¹ in the upper plate B¹. When, however, the baffles are swung in the dotted positions shown in 80 Fig. 2, they constitute a barrier across the rear end of the casing and direct the draft immediately to the ports E¹ and cut it off from the major portion of the front chamber B.

85 Communicating with the ports E¹ are vertically disposed flues E passing upwardly along either side of the fire-place opening A¹ and leading to any convenient main draft outlet or chimney O, and opening into it 90 above a chimney damper CD illustrated as an oscillatory flap valve or plate.

Thus it will be seen that when the baffles are in their full line position, hot gases from the fire pass through the port C² and travel 95 through the major portion of the interior of the chamber B, thus heating the whole of the surface B¹ which may be used as a hot plate or hob for the boiling of kettles, saucepans or other cooking utensils. By swinging 100 either one or the other of the baffles D into the dotted position the flue gases will pass in part directly into the flue E adjacent to that baffle, and in part from back to front of the chamber B before passing 105 around the other baffle into the flue E. In this manner one side of the hob is heated to a greater extent than is the other side. If it is desired that the hob should remain cool then both baffles are swung into the dotted 110 position.

Any convenient means may be employed

for controlling the movement of the baffles, but such operating means does not constitute part of the present invention. Moreover, the lower and upper structures of the stove 5 and that portion of it situated behind the webs B⁴ in Fig. 2 do not constitute a portion of the present invention, and are not consequently described in detail.

If desired, in place of or in addition to 10 the baffles D, cupboards or ovens may be provided within the chamber B, and access to such cupboards could be had through the front plate B³.

It is also within the present invention to 15 apply the hereinbefore described construction of front chamber to the stove described in my application for Letters Patent No. 312,852 filed July 23, 1919 and also to the stove described in my application for Letters Patent No. 312,854 filed July 23, 1919. In such applications it is convenient that the 20 front chamber B should form part of the base or structure of the stove and the vertical flues E may be concealed behind the reveals of the fire-place openings.

What I claim as my invention and desire to secure by Letters Patent is:

1. For a domestic stove having a fireplace and a chimney-damper, the combination of 30 a front chamber situated in front of the fireplace opening in the stove, baffles within the chamber, a flue connecting the interior of the rear portion of the chamber with the fire space of the stove, and flues extending from 35 the chamber into communication with the chimney above the chimney-damper, substantially as described.

2. For a domestic stove having a fire-place and a chimney-damper, the combination of 40 grate bars for said fire-place, which bars are disposed in a vertical plane, a front chamber situated in front of the said grate-bars, baffles within the said chamber, said chamber having a draft opening in the rear face 45 thereof opposite the grate-bars, and flues extending from the chamber into communication with the chimney above the chimney-damper, substantially as described.

3. For a domestic stove having a fire-place 50 and a chimney-damper, the combination of a front chamber situated in front of the fireplace opening in the stove, a flue connecting the interior of the rear portion of the chamber with the fire-place of the stove, 55 flues extending from the chamber into communication with the chimney above the chimney damper, and adjustable baffles within the said chamber, which baffles in one of their adjusted positions cut off the 60 draft from the major portion of the said chamber and direct it immediately to the flue ports, but in another position lead the draft into substantially all parts of the chamber before it is directed to the flue 65 ports, substantially as described.

4. For a domestic stove having a fire-place and a chimney-damper, the combination of vertically disposed grate bars for said fire-place, a chamber situated in front of the grate bars, said chamber having a draft-opening in the rear face thereof opposite the grate bars, flues extending from the chamber into communication with the chimney above the chimney damper, and adjustable baffles within the chamber, said baffles in one of their adjusted positions cutting off the draft from the major portion of the said chamber and directing it immediately to the flue ports but in another position leading the draft into substantially all parts 80 of the chamber before it is directed to the flue ports, substantially as described.

5. For a domestic stove having a fire-place and a chimney-damper, the combination of a chamber situated in front of the 85 fire-place opening in the stove, a flue connecting the interior of the rear portion of the chamber with the fire-space of the stove and flues extending from the chamber into communication with the chimney above the 90 chimney damper.

6. For a domestic stove having a fire-place and a chimney-damper, the combination of vertically disposed grate bars for the fire-place opening in the stove, a chamber situated in front of the said grate-bars, a draft opening in the rear face of the chamber opposite the grate bars, and flues forming draft outlets from said chamber.

7. For a domestic stove having a fire-place 100 and a chimney-damper, the combination of a chamber situated in front of the fire-place opening in the stove, a flue connecting the interior of the rear portion of the chamber with the fire-place of the stove, flues extending 105 from the chamber into communication with the chimney above the chimney-damper, said chamber forming a heating means for objects to be heated, and adjustable baffles within the said chamber, which baffles 110 in one of their adjusted positions cut off the draft from the major portion of the said chamber and direct it immediately to the flue ports, but in another position lead the draft into substantially all parts of the chamber before it is directed to the flue ports, substantially as described.

8. For a domestic stove having a fire-place and a chimney-damper, the combination of vertically disposed grate bars for the fire-place opening in the stove, a chamber situated in front of the grate bars, said chamber having a draft-opening in the rear face thereof opposite the grate bars, flues extending from the chamber into communication with the chimney above the chimney-damper, said chamber forming a heating means for objects to be heated, and adjustable baffles within the chamber, the baffles being so disposed that in one of their ad- 130

justed positions they cut off the draft from the major portion of the said chamber and direct it immediately to flue ports, but in another position they lead the draft into substantially all parts of the chamber before it is directed to the flue ports, substantially as described.

9. A domestic stove having a fire-place, a chimney therefor, means for controlling the draft through said chimney, a chamber in front of and communicating with said fire-place, a flue connecting said chamber and said chimney, and means for directing the draft from said fire-place into said chamber and thence through said flue, or from said fire-place directly through said flue into the chimney, substantially as described.

10. A domestic stove having a fire-place, a chimney therefor, means for controlling the draft through said chimney, a chamber in front of and communicating with said fire-place, a flue connecting said chamber and said chimney, and adjustable baffles for directing the draft from said fire-place into said chamber and thence through said flue, or from said fire-place directly through said flue into the chimney, substantially as described.

11. For a domestic stove having a fire

place and a chimney damper, the combination of a front chamber situated in front of the fire place opening in the stove, baffles within the chamber, a draft opening in the rear face of the chamber immediately in front of the fire space of the stove, and flues extending from the chamber into communication with the chimney above the chimney damper, substantially as described.

12. For a domestic stove having a fire place and a chimney damper, the combination of grate bars disposed in the vertical plane, a flat chamber situated in front of the grate bars, which chamber has a draft opening in its rear face opposite the grate bars, flues extending from the chamber into communication with the chimney above the chimney damper, and adjustable baffles which substantially fill the vertical dimension of the chamber and in one of their adjusted positions cut off the draft from the major portion of the chamber to direct it immediately to the flue ports but in another position lead the draft into substantially all parts of the chamber before it is directed to the flue ports, substantially as described.

In testimony whereof I have signed my name to this specification.

N. PEMBERTON-BILLING.
